Victor J. Evans

ATTORNEY.

UNITED STATES PATENT OFFICE.

NELS LARSON, OF CHICAGO, ILLINOIS.

TOY.

Application filed October 8, 1921. Serial No. 506,485.

To all whom it may concern:

Be it known that I, NELS LARSON, a citizen of the United States, residing at Chicago, in the county of Cook and State of Illinois, have invented new and useful Improvements in Toys, of which the following is a specification.

This invention relates to a toy and has for its primary object the construction of an inexpensive toy that will be very interesting to children.

An object of the invention is to provide a propeller and supporting same in a manner that the propeller may be rapidly driven by the mouth of the user.

A feature of the invention is the novel manner of combining the propeller and wind tube so that the former may be driven at high velocity to generate a sound.

With these and other objects in view the invention will be better understood from the following detailed description taken in connection with the accompanying drawing wherein:

Fig. 1 is a side elevation of the toy.
Fig. 2 is an end view.

Fig. 3 is an enlarged sectional view on the line 3—3 of Fig. 2.

Fig. 4 is a sectional view on the line 4—4

of Fig. 1.
Fig. 5 is a sectional view on the line 5—5

of Fig. 1.

Again referring to the drawing illustrating one of the many constructions of my invention the numeral 1 designates a plate bent to provide a body portion 2 and a tapering tube 3. This tube has one end 4 arranged to provide a mouth piece and its outlet end 5 arranged directly behind the blades 6 of the propeller 7. Thus it will be seen that when forcing air through the tube the air will escape from the outlet and strike against the blades for propelling the propeller at high velocity and in fact at such a velocity that a sound will be created thereby increasing the novelty of the toy.

I provide a novel form of bearing for the propeller so as to greatly reduce the expense of this bearing which consists of a tongue 8 stamped from the body of the propeller so as to receive and support, for rotation, the headed end 9 of a pin 10. It will also be noted that this pin 10 passes through a centrally arranged hole 11 in the propeller thereby giving a substantial bearing to the propeller, and further extends parallel to the plate with the end bent at right angles to be riveted in a hole 12 in the plate as indicated at 13. To accomplish more substantial connection I provide a tongue 14 outstruck from the plate.

From the foregoing description taken in connection with the accompanying drawing it will be apparent that I provide a toy of simple inexpensive construction that has a number of features that will appeal to a child.

It is, of course, to be understood that the invention may be constructed in various other manners and the parts associated in different relations and, therefore, I do not desire to be limited in any manner except as set forth in the claims hereunto appended.

Having thus described my invention what I claim is:

1. A toy comprising a plate bent to provide a body portion and a tapering air tube, a propeller and a pin connecting the propeller to the plate so that the propeller blades will be disposed adjacent to the outlet of said tube.

2. A toy comprising a plate bent to provide a body portion, and a tapering tube having a mouth piece and an outlet, a propeller consisting of a plurality of blades adapted to move in front of said outlet, said blade having an outstruck tongue, and a pin passing through said tongue and a portion of the propeller and secured to said blades.

In testimony whereof I affix my signature.
NELS LARSON.
